UNITED STATES PATENT OFFICE.

JOHN V. LONG, OF JERSEY CITY, NEW JERSEY.

ELECTRICAL BODY-WEAR.

SPECIFICATION forming part of Letters Patent No. 396,212, dated January 15, 1889.

Application filed February 28, 1888. Serial No. 265,586. (No model.)

To all whom it may concern:

Be it known that I, JOHN V. LONG, a citizen of the United States, residing at Jersey City, in the county of Hudson and State of New Jersey, have invented a certain new and useful Improvement in Electrical Body-Wear, of which the following is a specification.

The object of my invention is to prevent the occurring of involuntary seminal emissions, and thereby to assist in the cure of those diseases by which they are caused.

To this end my invention consists, mainly, in an electric circuit-controller constructed so as to be operated by the movement of the male genital organs, and to thereby affect a circuit whose effect is to awaken the user from sleep. I prefer that the circuit shall be arranged to administer an electric shock to the user to awaken him. It may, however, act in other ways, as by giving an audible alarm by means of a bell or vibrator. The preferred construction for the circuit-controller is that of a ring or collar carrying within it relatively-movable contacts, which will be forced together by the movement above referred to, to close a circuit. This circuit is preferably through a battery, induction-coil, and vibrator to terminals connected with the user's body, preferably rings placed upon his fingers. The connections are made by suitable flexible conductors.

My invention is illustrated in the accompanying drawings.

Figure 1 is a plan view of the preferred form of circuit-controller with the devices connected therewith, some of the connections being in diagram; and Fig. 2 is a horizontal section of the circuit-controller.

A is a collar of wood, hard rubber, or other suitable insulating material. This collar has an internal groove, a, on one side and a slot, b. At the end of said slot is pivoted the curved insulating-arm c, whose free end carries a metal pin, d, working in the slot b and connected by a flexible wire, e, with a binding-post, f, on the collar. The arm c is held forward by a flat spring, g, secured within the groove a. Upon the collar A is placed a metal clasp, h, carried by a screw, i, passing through the slot b and held adjustably by a nut, k, on said screw. To this clasp h is secured a cir-

cuit-wire, 1, the other circuit-wire, 2, being connected to binding-post f. I prefer to provide the collar with eyes l l, from which straps m m extend to a belt to assist in holding the device in position. The conductors 1 2 are joined in a flexible cord and include a battery, B, vibrator C, and the primary of an induction-coil, D. The secondary of the induction-coil is joined by wires united into a flexible cord, E, to two split metal rings, F F.

The operation of these devices is as follows: Upon retiring, the collar A is placed in position, as will be readily understood, and the rings F F are placed upon two fingers of the wearer. The battery and induction-coil will be placed in a box beneath the bed or in other convenient situation. The movement of erection will force the arm c back until the pin d makes contact with the clasp h, when the primary of the induction-coil will be closed and the user will receive a shock from the secondary through the rings F F sufficient to awaken him from sleep; or if it is found that the desired effect may be produced by the shock without awakening the patient the induction-coil may be adjusted in the well-known way for this purpose.

The position of the clasp h may be adjusted according to the extent of movement required for the arm c in each case.

What I claim is—

1. In a circuit-controller, the combination of a supporting-body so formed and constructed as to be capable of being supported in the situation hereinbefore indicated, and relatively-movable contacts carried within said body, substantially as set forth.

2. The combination, with a circuit-controller consisting, essentially, of a supporting-body so formed and constructed as to be capable of being supported in the situation hereinbefore indicated, and relatively-movable contacts carried within said body, of devices in a circuit connected with said contacts for awakening the user from sleep, substantially as set forth.

3. In a circuit-controller, the combination of a supporting-body so formed and constructed as to be capable of being supported in the situation hereinbefore indicated, and relatively-movable contacts carried within

said body and having their extent of movement adjustable, substantially as set forth.

4. The combination, with a circuit-controller consisting, essentially, of a supporting-body so formed and constructed as to be capable of being supported in the situation hereinbefore indicated, and relatively-movable contacts carried within said body, of an induction-coil whose primary is in the circuit controlled by said contacts and whose secondary has terminals adapted to be placed in contact with the user's body, substantially as set forth.

5. In a circuit-controller, the combination of a ring or collar of insulating material and relatively-movable contacts supported within the same, substantially as set forth.

6. In a circuit-controller, the combination of the ring or collar of insulating material, the contact-making arm pivoted upon and within said collar, and the stationary contact carried by said collar, substantially as set forth.

7. In a circuit-controller, the combination

of the ring or collar of insulating material 25 and the relatively-movable contacts supported within the same, the normal relative position of said contacts being adjustable, substantially as set forth.

8. In a circuit-controller, the combination 30 of the ring or collar of insulating material, the contact-making arm pivoted upon and within said collar, and the adjustable stationary contact carried by the collar, substantially as set forth.

9. In a circuit-controller, the combination 35 of the ring or collar of insulating material, the circuit-terminals upon the same, the arm pivoted within the collar, and the contact carried by said arm flexibly to one of said terminals and adapted to be moved into connection with the other, substantially as set forth.

This specification signed and witnessed this 25th day of February, 1888.

JOHN V. LONG.
